UNITED STATES PATENT OFFICE

ISIDORE KLEIN, OF BROOKLYN, NEW YORK

WINDOW FASTENER

Application filed March 23, 1929. Serial No. 349,342.

This invention relates to new and useful improvements in latches for windows or the like.

The invention has for an object the provision of a device of the class mentioned which is of simple durable construction, dependable in use and efficient in action, and which can be manufactured and sold at a reasonable cost.

10 The invention proposes the use of two separate latch sections, one for attachment upon one of the two members to be latched together, and the other for attachment on the second member, the first latch section to have a latch arm hingedly mounted and extendible across the second latch section, and the second latch section to have a latch arm pivotally mounted and movable across the said latch arm for holding the latch arm of 20 the first section in locked position.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:—

30 Fig. 1 is a front elevational view of two members to be latched together, and provided with a latch constructed according to this invention.

Fig. 2 is a horizontal sectional view taken 35 on the line 2—2 of Fig. 1.

Fig. 3 is a horizontal sectional view taken on the line 3—3 of Fig. 1.

Fig. 4 is a view similar to Fig. 2 but showing the latch in disengaged condition.

40 Fig. 5 is a fragmentary plan view of two members to be latched together and provided with the same latching means as shown in Fig. 1.

Fig. 6 is a transverse vertical sectional view taken on the line 6—6 of Fig. 5.

The reference numeral 10 indicates generally a stationary frame member 11 and a movable window which moves vertical relative to the stationary frame as seen in Fig. 1.

50 A latch section 12 is attached upon the sta-

tionary frame 10 and a second latch section 13 upon the movable window 11. The latch section 12 has a latch arm 14 hingedly mounted and extendible across the latch section 12 while the latch section 13 has a pivotally mounted latch arm 15 movable across the latch arm 14 for holding the latch arm 14 in a locked position. 55

The latch section 12 consists of a block 16 formed with a transverse groove 17 and a strip 18 is fixed on the base of the groove and has an upturned rear end 19. The latch arm 14 is hingedly connected to the front end of the strip 18 as at 20 and a spring 21 is coaxially mounted on the hinge 20 and 60 acts between the strip 18 and the latch arm 14 for normally urging the latch arm upwards against the upturned end 19 as seen in Fig. 4.

The second latch section 13 consists of a 70 block 22 secured upon the movable window member 11 and formed with a longitudinal flange 23 along one of its sides. This flange projects above the top surface of the block and the central portion of the flange is bent 75 at right angles to the main portion as indicated by reference numeral 23'. This provides a passage so that the latch arm 14 may pass between the sections of the flange and rest flat against the block 22. The latch arm 15 is pivotally mounted on the top of the block 22 as at 24 and is arranged to swing 80 across the top of the latch arm 14 when the latter arm is in its lowered position. The portion 23' of the flange has a cutout indicated 85 by numeral 25 in Fig. 3 so that the latch arm 15 may engage underneath. The free end of the latch arm is turned upwards to form a handle portion 26. A spring 27 is coaxially mounted on the pivot point of the latch arm 15 and acts between the block 22 and the latch arm for normally urging the latch arm 90 against the flange 23 as shown in Fig. 1. Dot and dash lines 28 indicate another position of the latch arm 15 to which it may be manually moved for permitting the spring 21 to raise the latch arm 14 to its raised position.

It is particularly pointed out that the latch arm 14 moves in a plane at right angles to the longitudinal length of the block 16. The 100

latch arm 15 moves in a plane parallel to the longitudinal length of the block 22. For this reason when the latch arm 15 is engaged across the top of the latch arm 14 it securely holds the same in a locked position. Persons attempting to jimmy the window may insert a knife or other implement between the stationary frame and the movable window but cannot move the latch arm 14 for causing an unlocking thereof.

In Figs. 5 and 6 the same latch has been shown applied to an inner and outer window sash for latching a window in a closed position. The reference numeral 29 indicates the outer window sash which has a horizontal bottom member 30 upon which the latch section 12 is attached. The inner window sash is indicated by numeral 31 and this sash has a horizontal top member 32 upon which the second latch section 13 is secured. Since the latch arm 14 of the latch section 12 extends across the second latch section 13 and is held in latched position by the pivoted arm 15 of this section the window sashes are locked. In Fig. 6 numerals 33 indicate the jamb members of a window frame in which the sashes operate.

In operation of the device the latch arm 14 is manually moved down into its latching position and the latching arm 15 pivoted across the top of the latch arm 14 for holding it in locked position. In this condition of the device the two members are latched together and cannot be moved. For opening the latch it is merely necessary to manually move the latch arm 15 against the action of the spring 27. As soon as the arm 15 is moved free from the arm 14 the spring 21 will automatically raise the arm 14 to its inoperative position. When the arm 15 is released, the spring 27 will urge the same against the flange 23 and the device will remain in this condition, in which the two members may be moved without interference.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A latch for windows, and the like, comprising a latch section for attachment on one of two members to be latched together, a second latch section for attachment on the other member, and said sections being arranged for connection, a latch arm hingedly mounted for moving in the vertical and on one section and engageable by a latch arm pivotally mounted for moving in the horizontal and on the other section and constitut-

ing the arrangement for connection between said sections.

2. A latch for windows, and the like, comprising a latch section for attachment on one of two members to be latched together, a second latch section for attachment on the other member, and said sections being arranged for connection, a latch arm hingedly mounted for moving in the vertical and on one section and engageable by a latch arm pivotally mounted for moving in the horizontal and on the other section and constituting the arrangement for connection between said sections, the pivoted arm being engageable over the hinged arm to hold down the hinged arm in latched position.

3. A latch for windows, and the like, comprising a block, a latch arm hingedly mounted thereon, arranged to move in a plane at right angles to the longitudinal length of the block, a second block with a projecting flange adjacent the first block, the central portion of the flange being turned inwards to form a passage for the latch arm, and a second latch arm pivotally mounted on the second block, arranged to move in a plane parallel to the longitudinal length of the block, and over the first latch arm when this arm is in latching position and underneath the said central portion.

4. A latch for windows, and the like, comprising a block with a transverse recess, a latch arm hingedly mounted therein, arranged to move in a plane at right angles to the longitudinal length of the block, a second block with a projecting flange adjacent the first block, the central portion of the flange being turned inwards to form a passage for the latch arm, and a second latch arm pivotally mounted on the second block, arranged to move in a plane parallel to the longitudinal length of the block, and over the first latch arm when this arm is in latching position and underneath the said central portion.

5. A latch for windows, and the like, comprising a block, a latch arm hingedly mounted thereon, arranged to move in a plane at right angles to the longitudinal length of the block, a second block with a projecting flange adjacent the first block, the central portion of the flange being turned inwards to form a passage for the latch arm, and a second latch arm pivotally mounted on the second block, arranged to move in a plane parallel to the longitudinal length of the block, and over the first latch arm when this arm is in latching position and underneath the said central portion, and means for moving the first latch arm into inoperative position.

6. A latch for windows, and the like, comprising a block, a latch arm hingedly mounted thereon, arranged to move in a plane at right angles to the longitudinal length of the

block, a second block with a projecting flange adjacent the first block, the central portion of the flange being turned inwards to form a passage for the latch arm, and a second latch arm pivotally mounted on the second block, arranged to move in a plane parallel to the longitudinal length of the block, and over the first latch arm when this arm is in latching position and underneath the said central portion, means for moving the second latch into operative position, and means for moving the first latch arm into inoperative position.

5 In testimony whereof I have affixed my
10 signature.
